(57) **CLAIM**

The ornamental design for a gaming machine component, as shown and described.

DESCRIPTION

FIG. 1 is a front, left side and bottom perspective view of the gaming machine component showing our new design;

FIG. 2 is a top, front and right side perspective view thereof;

FIG. 3 is a top plan view thereof;

FIG. 4 is a front elevational view thereof; and,

FIG. 5 is a right side elevational view thereof, the left side being a mirror image.

The features shown in broken lines form no part of the claimed design.
